US00D907089S

(12) **United States Design Patent** (10) **Patent No.:** **US D907,089 S**
Michaelian et al. (45) **Date of Patent:** **** Jan. 5, 2021**

(54) **VIDEO CAMERA**

(71) Applicant: **Dolby Laboratories Licensing Corporation**, San Francisco, CA (US)
(72) Inventors: **Peter Michaelian**, San Francisco, CA (US); **Samuel James Fleming Carr**, San Francisco, CA (US); **Christine Anna Livaudais**, San Francisco, CA (US); **Vincent Voron**, Menlo Park, CA (US)

(73) Assignee: **Dolby Laboratories Licensing Corporation**, San Francisco, CA (US)

(**) Term: **15 Years**

(21) Appl. No.: **29/660,874**

(22) Filed: **Aug. 23, 2018**

(51) LOC (13) Cl. **16-01**
(52) U.S. Cl. **USPC D16/202**

(57) **CLAIM**

The ornamental design for a video camera, as shown and described.

DESCRIPTION

FIG. 1 is a perspective view of a video camera showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the video camera which form no part of the claimed design.

The drawings include surface shading which illustrates contour and not surface ornamentation.

1 Claim, 3 Drawing Sheets
